Des. 188,103
Patented June 7, 1960

188,103

ELECTRICAL CONDUCTOR OF THE SUSPENDED CABLE TYPE

Donald H. Scofield, Redwood City, Calif., assignor to
Insul-8-Corp., San Carlos, Calif., a corporation of
California

Filed Mar. 26, 1959, Ser. No. 55,202

Term of patent 14 years

(Cl. D26—1)

Fig. 1 is a perspective view of an electrical conductor of the suspended cable type, showing my new design;

Figure 2 is a bottom plan view, the top being substantially a mirror image thereof; and

Fig. 3 is a side elevational view, the opposite side being substantially a mirror image thereof.

I claim:

The ornamental design for an electrical conductor of the suspended cable type, as shown and described.
